US00D793386S

(12) **United States Design Patent** (10) **Patent No.:** **US D793,386 S**
(45) **Date of Patent:** **** Aug. 1, 2017**

(54) **DIGITAL COMMUNICATION DEVICE**

(71) Applicant: **BLUEBIRD INC.**, Seoul (KR)

(72) Inventors: **Jung Sik Park**, Seongnam-si (KR);
Hack Nam Yoon, Bucheon-si (KR);
Jang Won Lee, Seoul (KR)

(73) Assignee: **BLUEBIRD INC.**, Seoul (KR)

(**) Term: **15 Years**

(21) Appl. No.: **29/534,333**

(22) Filed: **Jul. 28, 2015**

(30) **Foreign Application Priority Data**

Jan. 29, 2015 (KR) 30-2015-0004991

(57) **CLAIM**

The ornamental design for a digital communication device, as shown and described.

DESCRIPTION

FIG. 1 is a front perspective view of a digital communication device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof shown enlarged for ease of illustration; and,

FIG. 7 is a bottom plan view thereof shown enlarged for ease of illustration.

The broken lines shown in the drawings illustrate portions of the digital communication device that form no part of the claimed design.

1 Claim, 7 Drawing Sheets
